M. WARREN
HEATING APPARATUS

1,860,639

Filed April 20, 1931

UNITED STATES PATENT OFFICE

MARLIN WARREN, OF DETROIT, MICHIGAN

HEATING APPARATUS

Application filed April 20, 1931. Serial No. 531,477.

My invention relates to a new and useful improvement in a heating apparatus adapted for use in heating buildings and the like in which hot air may be produced by bringing the same into contact with steam heated bodies and bodies heated by hot water.

It is an object of the present invention to provide an apparatus of this class in which a force circulation of air would be effected and a compact, durable structure provided.

Another object of the invention is the provision in an apparatus of this class of means for humidifying the air which is circulated and heated.

Another object of the invention is the provision of an apparatus in which a maximum heating area is presented to the air which is being circulated.

Other objects will appear hereinafter.

The invention consists in the combination and arrangement of parts hereinafter described and claimed.

The invention will be best understood by a reference to the accompanying drawings which form a part of this specification, and in which,

Fig. 1 is a side elevational view of the invention.

Fig. 2 is a central vertical sectional view of the invention.

Fig. 3 is a sectional view taken on line 3-3 of Fig. 2.

Fig. 4 is a fragmentary sectional view of the invention illustrating the humidifier.

In the device I provide supporting legs 9 which serve to support the superstructure comprising an outer shell or housing 10 enclosing an inner shell or housing 11 which is positioned within and spaced from the outer shell or housing. Communicating with the interior of the inner housing or shell 11 is a blower pipe 12 which is connected to the blower 13 driven by the electric motor 14 and which serves to deliver to the interior of the inner shell or housing 11 a quantity of air.

A plurality of tubes 15 project through the space separating the inner housing and the outer housing. A top 16 and a bottom 17 serve to close the space between the inner shell or housing and the outer shell or hous-

ing to provide a compartment 18 into which water may be delivered by the pipe 19 which is connected by the pipe 20 through the valve 21 to a suitable source of water supply. The water in the compartment 18 is preferably maintained at the level 22. A plurality of pipes 23 connect opposite sides of this compartment 18 at the top and bottom so as to provide for the circulation of the water and the distribution of the heat by convection. The tubes 15 are traversed by the water tubes 24. The pipe 19 is connected through the T 25 to the pipe 26 to the hot water heater 27 which is in the nature of a gas hot water heater, the gas pipe 28 being illustrated as located in the customary position on such heaters. The hot water pipe 29 leads from the hot water heater and communicates with the compartment 18. A gauge glass 30 is connected with the compartment 18 so as to indicate the amount of water in the compartment 18.

A steam blow-off valve 31 is connected in communication with the compartment 18 above the normal water level by the pipe 32. A by-pass 33 connects the pipe 32 with the air inlet pipe 12 so as to humidify the air which is delivered into the interior of the shell 11. A corrugated covering 34 is provided for three sides of the outer shell 10, these corrugations forming vertical channels or flues 35.

In operation, the gas burner serves to heat the water which circulates through the compartment 18 and this water will heat the surface with which the air will be brought into contact. Pipes 36 travel the interior of the shell 11 and the air brought into the interior of the shell 11 will pass upwardly and contact with these pipes 36. Similarly, that portion of the air which passes through the conduits 15 will contact with the pipes 24 and thus the air will become heated. The portion of the air passing through the tubes or conduits 15 will pass upwardly in the passages 35 and thus inducing a draft from the bottom of the passages drawing more air upwardly into the hood or cover 37, from which leads the flue 38 and to which suitable piping may be connected to conduct the hot air to any desired location.

It is obvious that a simple and compact structure is provided whereby a hot air heating system is established with the use of hot water as the heating agent.

5 6 When desired, an electric heating element 39 supported by the brackets 40 may be used as an auxiliary heater.

10 While I have illustrated and described the preferred form of construction of my invention, I do not wish to limit myself to the precise details of structure shown, but desire to avail myself of such variations and modifications as may come within the scope of the appended claims.

15 18 Having thus described my invention, what I claim as new and desire to secure by Letters Patent is:

20 21 1. A heater of the class described, comprising: an inner shell; an outer shell spaced from and enclosing said inner shell; a plurality of tubes traversing said inner shell and communicating at opposite ends with the space between said inner shell and said outer shell; conduits extending through the space 25 26 between said inner shell and said outer shell and communicating with the interior of said inner shell and the exterior of said outer shell; a plurality of pipes communicating with the space between said inner shell and said outer shell and traversing said conduits; and means for delivering air into the interior of said inner shell.

30 31 2. A heater of the class described, comprising: an inner shell; an outer shell spaced from the enclosing said inner shell; a plurality of tubes traversing said inner shell and communicating at opposite ends with the space between said inner shell and said outer shell; conduits extending through the space 35 36 between said inner shell and said outer shell and communicating with the interior of said inner shell and the exterior of said outer shell; a plurality of pipes communicating with the space between said inner shell and said outer shell and traversing said conduits; means for delivering air into the interior of said inner shell; means for delivering hot water into the space between said shells; a cover for said outer shell and providing there- 40 41 42 43 44 45 46 47 48 49 50 with a plurality of vertically extended passages; and a hood covering said shells and said passages.

55 In testimony whereof I have signed the foregoing specification.

MARLIN WARREN.
